CAR ROOF

Charles David Bonsall, Pittsburgh, Pa., assignor
to P. H. Murphy Company, New Kensington,
Pa., a Corporation of Pennsylvania

Application July 2, 1931. Serial No. 548,304

3 Claims. (Cl. 108—5.4)

This invention relates to metal car roofs of the type wherein the roof sheets span from side plate to side plate and are so shaped and secured together that they form a series of ribs alternating with channels, and the roof covering as a whole functions mechanically after the manner of a beam.

The principal object of the present invention is to strengthen and stiffen the seam construction and thus increase the load-carrying capacity and 10 rigidity of the roof. Another object is to prevent any water that may enter the seams from reaching the interior of the car. Another object is to utilize the space within the roof ribs to accommodate 15 the seam reinforcing members. Another object is to provide strut members between adjacent seam stiffening members that are adapted to strengthen the roof and constitute load-lifting beams. Another object is to utilize the 20 space within the roof ribs to accommodate the combined struts and load-lifting beams. Other objects are simplicity and cheapness of construction, fewness of parts and compactness of 25 design.

25 The invention consists in the parts and in the arrangements and combinations of parts hereinafter described and claimed.

In the accompanying drawings, which form 30 part of this specification and wherein like symbols refer to like parts wherever they occur.

Fig. 1 is a plan view of a portion of a car roof embodying my invention.

Fig. 2 is a vertical transverse section through one-half of the roof on the line 2—2 in Fig. 1.

35 Fig. 3 is a vertical longitudinal section through the roof at the ridge on the line 3—3 in Fig. 1.

Fig. 4 is an enlarged fragmentary section similar to Fig. 3.

Fig. 5 is a section on the line 5—5 in Fig. 3.

40 Fig. 6 is a vertical longitudinal section taken along the ridge line of a roof of modified construction; and

45 Figs. 7, 8 and 9 are fragmentary vertical sections showing modified forms of seam stiffening members.

In the construction illustrated in Figs. 1 to 5, inclusive, the roof is made up of a series of similar roof sheets offset vertically at or adjacent to the medial line so as to form an upper panel 1 with a depending flange 2 along its side margin and a lower panel 3 with an upstanding flange 4 along its side margin, the two panels being connected together substantially midway of the side margins of the sheet by an upstanding web 5. Thus, one-half of each roof sheet is in the form

of a flat-topped hollow rib A, and the other half of the sheet is in the form of a flat-bottomed channel B. Near the eaves of the car, the height of the rib A decreases until it merges into the plane of the bottom of the channel B at the side plates 6 of the car, over which they are turned down and secured thereto. The roof sheets are so arranged on the car that the depending side marginal flange 2 of the rib A of one sheet overlaps the upstanding side marginal flange 4 of the channel B of an adjacent sheet, thereby forming a roof wherein the ribs A extend crosswise of the car alternately with the channels B.

The seams formed by the overlapped side marginal flanges 2 and 4 of adjacent roof sheets are stiffened and strengthened by a reinforcing member 7 of substantially inverted T-shaped cross-section. Each of these inverted T-shaped seam reinforcing members extends from side plate 6 to side plate 6 and is rigidly secured thereto with its upstanding stem 8 located within a hollow roof rib A and rigidly secured by rivets 9 flatwise to the side wall thereof formed by the overlapped flanges 2 and 4 of adjacent roof sheets. A metal strip 20 extends lengthwise of each seam between the outside heads of the rivets 9 and the depending seam flange 2 of each roof sheet and serves to prevent the sheet from buckling between rivets and the rivet heads from pulling through the sheet. The seam reinforcing members 7 are arranged with their bottoms substantially flush with the underside of the lower level of the roof and with one of its base flanges 10 extending beneath the bottom 3 of an adjacent channel which is offset upwardly, as at 11, to accommodate said flange. The base flanges 10 of the seam reinforcing member 7 have their marginal portions offset upwardly to provide longitudinal waterways 12 for carrying off any water that may leak through the seams.

The roof is further stiffened and strengthened by means of a member 13 located wholly within each roof rib A. Said member is disposed longitudinally of the roof preferably at the ridge with one end resting on and rigidly secured to the upwardly offset margin of the adjacent base flange 10 of the seam reinforcing member 7 and with the other end secured by rivets 14 to the web portion 5 of the sheet. The securing rivets 14 for the last mentioned end of the member 13 are prevented from pulling through the web 5 by means of a Z-shaped plate 15 arranged with its web between the outer heads of the rivets 14 and the web 5 of the sheet and with its flanges 16 overlapping the adjacent margins of the rib A.

and channel B, respectively. The members 13, which serve as struts to stiffen the roof, are made of such shape and are otherwise adapted to serve as load-lifting beams to which lifting tackle or other devices may be secured. Preferably, such members are made in the form of an inverted channel with lateral flanges 16 adapted to be engaged by slidable tongs or similar devices. The flanges 16 of the member 13 are preferably inclined upwardly to form waterways 17 for delivering to the waterway 12 any water that may leak around the rivets 14.

By the arrangement described, the reinforcing member 7 for each seam serves to stiffen and strengthen the whole roof and is located entirely between the upper and lower levels of the roof thereby obtaining a maximum headroom inside of the car. The roof is further strengthened by the strut members 13, which also function as load-lifting beams and are also located between the upper and lower levels of the roof with clear spaces between said members and the undersides of the roof ribs so as to permit the rope or chain of lifting tackle to be passed over said members. In the event that any of the rivets 9 work loose or are improperly driven, any water that leaks around said rivets or between the seam flanges 2 and 4 will be deposited in the waterways 12 in the flanges 11 of the seam reinforcing members 7 and discharged over the side of the car. Likewise, any water that leaks around the rivets 14, which secure the combined struts and load-lifting beams 13 to the webs 5 of the roof sheets, will be conveyed by the waterways 17 at the sides of said beams to the waterways 12 in the seam reinforcing member 7 and thence outside of the car.

In the modified roof construction shown in Fig. 6, the roof sheets are made in the form of channels and are arranged alternately in two series, the sheets of one series being arranged with the channel opening downwardly to form ribs A' and the sheets of the other series being arranged with the channel openings upwardly to form channels B'. The depending side flanges 2a of the ribs A' overlap and are riveted to the upstanding flanges 4a of the channels B'. Seam stiffening members similar to the inverted T-shaped seam stiffening members 7 are located within the hollow roof ribs A' with their stems secured to the lapped seam flanges 2a and 4a by means of the securing rivets therefor. The seam stiffening members are connected at the ridge by members 13a that are located within the hollow ribs A' with their ends resting on and riveted to the opposing base flanges of adjacent seam reinforcing members. The members 13a serve as combined struts and load-lifting beams and have the same cross-sectional shape as the member 13.

Fig. 7 shows a seam stiffening member 7a in

the form of an inverted channel with outstanding base flanges, the overlapped seam flanges of the roof sheets being secured to one side wall of said channel and the combined strut and load-lifting beam having its end supported on and riveted to the base flange of said seam stiffening member.

Fig. 8 shows a seam stiffening member 7b of substantially L-shaped cross-section, with the lapped seam flanges secured to its vertical flange and with one end of the combined strut and load-lifting beam secured to the other flange.

Fig. 9 shows a seam stiffening member 7c of Z-shaped cross-section with the lapped seam flanges secured to the vertical web portion of said member with the sheets at the two levels supported on the upper and lower flanges, respectively, of the seam stiffening member. The combined strut and load-lifting beam is supported within the roof rib by means of an angle bracket 18, one flange of which is secured to the web of the Z-shaped seam reinforcing member 7c by the rivets that secure the lapped sheet flanges thereto. One end of the combined strut and load-lifting beam rests on and is riveted to the other flange of the angle bracket 18.

What I claim is:

1. A car roof comprising roof sheets adapted, arranged and rigidly joined together at their edges to form alternating ribs and channels extending transversely of the roof, a reinforcing member secured to one side wall of a rib, and a strut member extending from said reinforcing member to the other side wall of said rib and secured to said wall by horizontal rivets, said reinforcing member and said strut member having longitudinal waterways formed therein, the waterways of said strut being located below said rivets and communicating with the waterways of said reinforcing member.

2. A car roof comprising roof sheets adapted, arranged and riveted together at their edges to form alternating ribs and channels, reinforcing members secured to one side wall of said ribs by the rivets that secure the sheets together at their edges, strut members located within said ribs with one end riveted to the other side wall thereof and with the other end secured to the reinforcing member therein, and metal strips located beneath the outer heads of the securing rivets for said seam reinforcing members and said sheets.

3. A car roof comprising roof sheets adapted, arranged and rigidly riveted together at their edges to form alternating ribs and channels, reinforcing members secured to one side wall of said ribs by the rivets that secure the sheets together at their edges, and metal strips located beneath the outer heads of the securing rivets for said seam reinforcing members and said sheets.

CHARLES DAVID BONSALL.
